ware

Application July 18, 1932, Serial No. 623,071
In Great Britain July 29, 1931

14 Claims. (Cl. 179—8.5)

- The present invention relates to telephone systems and is more particularly concerned with systems employing register controllers of the code translating type in which series of impulses transmitted by the calling subscriber and representing the exchange code are received by the register controller and translated into series of impulses having no relation to the impulses received from the calling subscriber.
- 10 The principal object of the invention is to provide a register controller of the above type particularly suitable for use in a rural exchange system of small capacity. In a system of this type it is probable that a certain number of the 15 subscribers associated with the rural exchange will be party line subscribers. Since such subscribers are not provided with automatic meters to assess the charge for a call it will be appreciated that on a call to a distant exchange an 20 operator will have to be brought in to complete the connection and assess the call.

According therefore to one feature of the invention in such a system when a connection originates from certain types of calling lines the 25 register controller employed in setting up the connection is arranged to transmit a series of routing digits characteristic of the calling line. It will be appreciated that the invention is not limited to party line subscribers but is capable 30 of application to other types of calling lines for instance to subscribers setting up a connection from a public call office. Further in view of the somewhat different nature of the work involved it is convenient that calls from party lines and 35 coin box subscribers should be routed to different operators for the assessment of the charge.

In the system described in the detailed description it is assumed that the rural exchange is situated near to a main exchange. Further 40 all outgoing calls from the rural exchange are extended through the main exchange and consequently if the provision of an additional rank of switches at the main exchange is to be avoided, it is necessary that the exchange codes of both 45 the rural exchange and main exchange should be the same. Special discriminating means must therefore be provided in the register controllers at the rural exchange since the dialling of the exchange code is not sufficient to determine the 50 destination of the calling and according to a further feature of the invention discrimination is effected in the register controllers located at the rural exchange in accordance with the first untranslated digit stored in the register controller. It will be noted that with this arrange-

ment both local subscribers to the main exchange and subscribers on the rural exchange will be accessible over different levels of the same rank of switches.

A still further feature of the invention relates to the provision of a selector switch for use in conjunction with a register controller at the rural exchange and which may function either as a final selector switch if the call is a local one or as a first code selector switch if the call is for 65 another exchange. In order to maintain a uniform numbering scheme provision is made according to a further feature of the invention for absorbing certain digits when a local call is set up directly by the calling subscriber, in which case 70 the register controller is released.

A further feature relates to an arrangement for enabling a party line subscriber to call another party line subscriber on the same line by dialling his ordinary directory number, the trunk 75 relay group associated with the code or local selector alone being connected up.

Further features of the invention relate to arrangements for catering for party lines having a large number of subscribers on the same line 80 say up to ten and for enabling party line subscribers to become individual line subscribers without changing their number.

The invention will be better understood from the following description of one method of carrying it into effect, taken in conjunction with the accompanying drawings comprising Figs. 1 to 12 which should be arranged as shown in the key sheet contained in Fig. 9 to form a complete circuit. Figs. 1, 2 and 3 show a subscriber's line 85 circuit together with a line finder associated with the line circuit over a finder distributor FDS shown in Fig. 3; Figs. 4 and 5 show a selector switch directly associated with the finder switch and adapted to operate as a final selector or 90 a first code selector depending upon whether the call is local or for a distant exchange. When operating as a first code selector the switch provides access to 10 outgoing junctions, while when operating as a final selector the switch has access 95 to 100 subscribers' lines. Meter discrimination up to 6 zones is provided on calls originated by regular subscribers. Figs. 6, 7, 8 and 9 show a register controller which in addition to performing the well-known functions provides three different translations for the same digits dialled according to the type of calling line, and further on local calls provides discrimination on the first 105 numerical digit. The register controller is associated with the selector switch over a selector 110

finder switch SFS which in turn co-operates with a translating distributor switch shown in Fig. 10 to associate the selector switch with an idle register controller. Figs. 11 and 12 show the 5 ringing, tone and pulse supply circuit.

Returning now to the assembled circuit and assuming that the subscriber associated with the line circuit shown in Fig. 1 originates a call a circuit is completed by way of his instrument 10 over conductors 10 and 11 to energize relay LK over its resting armatures lk_3 and lk_4 . Relay LK makes a first stage operation only in this circuit to close the light armatures lk_1 and lk_2 , and the high non-inductive resistance which is 15 included in its operating circuit and shown to the left-hand side of the coil ensures that the resistance of the subscriber's circuit has no appreciable effect on the operation. Relay LK at armature lk_1 extends battery from the coil to 20 mark the calling subscriber's position in the rotary bank multiple, and at armature lk_2 extends battery over the level start common 12 to mark the calling level in the vertical bank multiple and at the same time operating the common start 25 relay S, Fig. 3, by way of the resistance 13. Relay S at armature s_1 completes a circuit for operating relay V over both its windings in series, and at armatures s_2 and s_3 completes the circuit for the delayed alarm relay set TA and TB, the 30 function of which will be described later. It should be explained at this point that the distributor switch FDS is preselecting so that it always positions its wipers in engagement with a free finder such as that shown in Fig. 2 and if 35 at the instant the call is made the wipers are resting on contacts extending to a finder which is already in use, the following circuit is completed for advancing the wipers into engagement with the next free finder: earth on wiper $5a$ and bank contact, derived from the operated armature $1h_3$ in the case of a finder which is already switched or alternatively, by way of the off-normal springs 1N2 and resistance 14 in the case 40 of a finder which is performing its setting movement, upper low resistance winding of relay V, armature v_2 , interrupter springs fam , right-hand winding of relay G to battery. Owing to its high resistance relay G only is operated in this circuit and at armature g_1 energizes the driving magnet 45 FDM to prepare for the advancement of the wipers on to the next set of bank contacts. At 50 the conclusion of the magnet stroke the interrupter springs fam open the circuit to relay G which releases and in turn de-energizes the driving magnet FDM so that the wipers move into the next position. By this means an alternate 55 action takes place between relay G and the magnet until the wipers are moved into engagement with the next available finder, in which position 60 wiper $5a$ encounters an idle marking battery extended from the resistance 15 and the resting contact of the off-normal springs 1N2, whereupon the driving circuit is terminated since there is now no circuit for operating relay G. Consequently upon the operation of the start relay S, relay V then operates over both its windings in series, and the low resistance of the marking battery is sufficient to short-circuit relay G against operation at this time. Relay V provides 70 an alternative locking circuit for itself at armature v_1 to battery by way of resistance 16 which is of approximately the same resistance as the idle marking battery 15, and at armature v_2 opens the circuit to relay G and short-circuits its 75 lower winding so that the relay then holds over

the low resistance upper winding thereby effectively guarding the finder taken into use from selection by another distributor. Relay V moreover at armature v_7 extends battery by way of resistance 17, wiper $6a$ and bank contact of the 80 switch FDS, conductor 18, resting contacts of armature $1h_6$ in the finder selected, lower speaking conductor 19 to operate relay L, Fig. 4, of the associated selector over its lower winding. Relay L at armature l_1 operates relay B and at the same time removes earth from the release 85 trunk conductor 20 extending to the release magnet circuit of the finder. Relay B, Fig. 4, of the selector in turn operates relay BB shown in Fig. 5 which at armature bb_1 , Fig. 4, connects earth to the release trunk conductor 21 to guard the 90 circuit and prepare for the subsequent holding of the preceding switches.

Furthermore, relay V in the distributor circuit at armature v_9 completes a circuit for energizing the vertical magnet of the finder over wiper $8a$ and bank contact of the switch FDS and conductor 22, and at the conclusion of the magnet stroke when the wipers are raised to their first position, the springs vm will close thereby applying earth to conductor 23 which completes a circuit over bank contact and wiper $4a$ of the switch FDS to energize relay G over its right-hand winding. In this manner relay G is now caused to interact with the vertical magnet of the finder so 100 that the wipers are raised to the marked level. Towards the end of the first vertical step, the off-normal springs are operated thereby at springs 1N1 preparing a circuit to the release magnet ZM, at springs 1N2 connects up earth by way of 110 the resistance 14 to the bank contact of the switch FDS, and at springs 1N3 removes battery from the lower winding of relay 1H. The connection of earth by way of the off-normal springs 1N2 to the bank contact of the finder distributor is 115 without effect at this time since the circuit is already guarded from earth extended via the winding of relay V, but the feature is necessary to guard the finder against selection when the wipers are moved from their normal position 120 during exchange tests.

When the wipers of the finder are raised to the marked level the vertical wiper VW encounters the marking battery extended from the level start conductor 12 in the line circuit, and consequently 125 when relay G operates due to the closing of the springs vm at the end of the vertical movement, a locking circuit is then completed from battery on the vertical wiper VW over conductor 24, bank contact and wiper $2a$ of the switch FDS, 130 low resistance left-hand winding of relay R, armatures r_1 and r_2 , left-hand winding of relay G to earth. Relay G is therefore held operated to terminate the vertical setting movement, and relay R is also operated on both its windings in 135 series from earth supplied by way of armature g_3 .

When relay R is fully operated it locks over its low resistance left-hand winding and opens the holding circuit to Relay G; at armatures r_2 , r_3 and r_4 supplements the operation of the start relay 140 S which releases owing to the application of guarding potential by way of the low resistance winding of relay R to the vertical bank, at armature r_5 the circuit is opened to the driving magnet of the distributor and at armature r_6 the driving 145 circuit to the finder is transferred by way of wiper $7a$ and bank contact over conductor 25 to the rotary magnet RM. Upon the release of relay G the rotary magnet is energized to advance the wipers of the finder into engagement with the 150

level selected, and at the conclusion of the magnet stroke, springs rm are closed thereby completing a circuit for re-operating relay G which may be traced from: positive at the armature $v4$, 5 Fig. 3, wiper $3a$ and bank contact of the switch FDS, conductor 26, lower winding of relay $1H$, armature $1h1$, springs rm , conductor 23, bank contact and wiper $4a$ of the switch FDS, armature $v3$, winding of relay G to battery. Alternatively 10 in case the first set of contacts in the bank are not those marked, wiper P will encounter earth or a disconnection depending upon the condition of the line circuit connected therewith. In the case when earth is present on the contact 15 signifying that this line circuit is in use, a circuit will be completed by way of the upper winding of relay $1H$ which augments that already traced via the wiper of the distributor. In this manner relay G interacts with the rotary magnet RM to 20 bring about the advancement of the wipers into engagement with the calling line which is marked by the presence of battery potential through the winding of the cut-off relay LK . Towards the end of the first rotary step the rotary off-normal 25 springs operate thereby opening a circuit to the switching relay $1H$ which is effective for guarding purposes in case the associated selector is taken into use for test purposes.

Under these circumstances the engagement of 30 the selector other than over the normal route will be indicated by the application of earth to the release trunk conductor 21 and finds a circuit by way of the springs $1NR1$, lower winding of relay $1H$ to battery by way of the off-normal springs 35 $1N3$. Relay $1H$ is operated in this circuit and at armature $1h3$ connects earth to the corresponding contact in the bank of the distributor switch FDS to guard the finder against selection.

Returning now to the normal progress of the 40 call, when the wipers are moved into engagement with the calling line, relay G is short-circuited against further operation by the presence of marking battery encountered by wiper P , which also serves to operate the switching relay $1H$ over 45 both its windings in series. Relay $1H$ at armature $1h1$ completes a locking circuit for itself over its upper low resistance winding to earth on the release trunk conductor 21 from the associated selector, at armature $1h3$ connects direct earth 50 over conductor 27 to busy the circuit in the distributor bank, and at armatures $1h6$ and $1h7$ extends the calling subscriber's instrument circuit to the associated selector. Relay LK of the 55 calling circuit is fully operated in series with the switching relay $1H$ in the finder to clear the line of its normal battery and earth connections, and at armature $lk5$ removes battery from the level start common 12. Relay V is short-circuited and released by the connection of direct earth at armature $1h3$ and when the armature $v2$ becomes 60 normal, relay G is re-energized in series with the upper low resistance winding to complete a circuit for the driving magnet FDM in order that the wipers of the distributor shall be moved out of 65 engagement with the busy finder.

In case the next finder is also in use the distributor FDS will continue its hunting operation in the manner already described to preselect the first available finder preparatory to the reception 70 of a further call.

It should be explained that two distributors such as FDS and associated relays are provided and although the second is not shown in detail the associated start relay $1S$ and change-over 75 contacts are indicated to the left-hand side of

Fig. 3. Both distributor switches have access to the same group of line finders, the arrangements being such that if one switch fails the other switch takes over the duty and the necessary changeover is made from a delayed timing set 80 in a manner which will now be described.

Assuming that the finder taken into use fails to switch through within a reasonable period of time the continued operation of relay S or R maintains earth to the start terminal TPS extending to Fig. 11 for the purpose of setting in operation the tone and time pulse equipment whose detailed operations will be fully described later. It will be sufficient at this period to say that after a short interval earth is connected to the terminal FDS from this equipment which serves to operate relay TA over its right-hand winding so that the relay then locks over its left-hand winding to earth on armature $s4$, or alternatively earth by way of the resting armature $1h4$ of the finder taken into use. Relay TA moreover at armature $ta2$ connects one winding of relay TB to the terminal FDZ and after a time interval of conveniently 9 seconds after the application of earth to the terminal FDS , an earth 100 pulse is then connected to the other terminal FDZ which serves to operate relay TB which locks over its other winding in circuit with a resting armature of relay TB in the auxiliary distributor circuit to earth over conductor 57 supplied by way 105 of an alarm circuit not shown. Relay TB moreover at armature $tb2$ releases relay TA and at armature $tb3$ transfers the start circuit to relay $1S$ so that all further calls will be completed over the auxiliary distributor.

Incoming junctions from other exchanges are 110 terminated after the fashion of an ordinary subscriber's line on a combined line and cut-off relay such as LK , and in order that incoming calls shall not be delayed owing to the distributor being 115 busied in the process of connecting up a local call, the start circuit from LK relays of incoming junctions is diverted to bring about the operation of the start relay $1S$, so that all junction calls are completed by way of the auxiliary distributor which is not normally used for local calls. 120 Such an arrangement has the effect of speeding up the incoming traffic and is particularly desirable in cases where the finder has to locate the calling line between successive digits.

Since the finders are required to serve 100 lines only there is no limitation as to the number of wipers available and hence-forth wire metering may be adopted with advantage owing to the fact that metal rectifiers will not be required in 130 the meter circuit and the necessity for a booster battery installation also disappears. Meters are not provided on party lines and the meter contacts on the party line level are wired back to the vertical bank of the selector for a purpose 135 which will be described later.

Referring now to Figs. 4 and 5 this circuit is arranged to serve four different types of traffic which may be classified as follows:—

- (a) Calls incoming from a distant exchange. 140
- (b) Local subscribers desiring local connection.
- (c) Local subscribers requiring a distant exchange.
- (d) Revertive calls.

The first two types may again be sub-divided 145 according to whether the called party is situated on an individual or a party line.

Considering first a call incoming from a distant exchange, it should be explained that the bothway junction lines terminate in the local ex- 150

change on level 1 of the line finders, and consequently when the finder selected switches on this level, earth is extended by way of the operated armature $1h4$, Fig. 2, vertical wiper VW and first bank contact, conductor 28, to operate relay LO , Fig. 4, of the associated selector. It should also be noted that as this exchange is not arranged for tandem traffic, all calls incoming from a distant exchange are intended for local subscribers, and therefore, as a result of the discriminating signal extended over conductor 28, relay LO in operating converts the switch into a final selector, in order that the wipers may be set both in a vertical and rotary direction under the control of impulses.

The incoming junction extended by way of the wipers and the switching relay armatures of the finder taken into use, completes a circuit for the line relay L , Fig. 4, which in turn at armature $l1$ closes a circuit for relay B . Relay B operates and at armature $b1$ closes a circuit for relay BB , Fig. 5. Relay BB at armature $bb1$, Fig. 4, connects earth to the release trunk conductor 21 to guard the switch and hold operated the switching relay $1H$ of the finder and relay LK of the line circuit terminating the junction, and moreover at armature $bb3$, Fig. 4, operates relay C on its upper winding. Owing to the operation of relay LO immediately the switch is seized, circuits are opened at armatures $lo1$ and $lo8$ extending to the register controller group, since the switch is to function as the final selector and there is no question of storing or translation. As the call in question is originated from the first numerical selector level of the main exchange there remains with the particular numbering scheme chosen, three digits to be used in the local office, and as the switch therein will be set by the last two digits only, it is necessary that the first of the three shall be absorbed.

For all incoming calls the first digit received at the local exchange is 7, and in response thereto relay L is impelled and at each de-energization completes the following circuit for energizing the vertical magnet $2VM$ in order that the wipers may be stepped to the 7th level: earth at the resting springs of armature $l1$, Fig. 4, armatures $ba2$, $bb2$, $2h4$ and $c1$, low resistance lower winding of relay C , armature $e1$, winding of vertical bank $2VM$ to battery. Towards the end of the first vertical step the off-normal springs are operated thereby at springs $2N1$ opening the initial energizing circuit to relay C , at springs $2N2$, Fig. 5, a point is closed in the circuit of the release magnet $2ZM$ and at springs $2N3$, Fig. 5, a point is prepared in a tone circuit which becomes effective in case the desired subscriber is unavailable. Although the original energizing circuit to relay C is now opened, the relay remains held during the impulsion period over its lower winding by reason of the copper slug surrounding its core. Relay B is similarly equipped with a copper slug in order that it shall be held operated continuously during the impulsion period. At the conclusion of impulsion when the wipers are set opposite the 7th level, relay L is then held operated for an extended period, so that relay C releases after a short interval and the following circuit is completed for energizing the release magnet in order that the shaft and wipers shall be restored to the normal position: earth at armature $2h2$, Fig. 5, armature $rc1$, springs $2N2$, armatures $b2$ and $lo3$, rotary off-normal springs $2NR1$, armatures $c2$, 75 and $da2$, vertical bank contacts VB which are

bridged by the vertical wiper $1VW$ in the 7th position, winding of the release magnet $2ZM$ to battery. The release magnet in energizing locks itself in a circuit completed by way of its own armature $2zm1$ to ensure the full release of the shaft to the normal position, and at armature $2zm2$ prepares an operating circuit to relay DA which it will be noticed is held short-circuited at this time from earth which energizes the release magnet.

When the shaft and wipers are fully restored the off-normal springs $2N2$ again open, and as relay DA is no longer short-circuited, it operates in series with the release magnet $2ZM$ and locks for the remainder of the connection over its other winding to earth at armature $bb4$, Fig. 4. Relay DA at armature $da2$ prepares a circuit for operating relay E at the conclusion of the next impulsion period, and at armatures $da5$, $da6$ and $da7$ establishes connection with the upper set of wipers negative 1, positive 1 and $P1$ which have access to the local hundred group of lines.

The second digit received again steps the shaft and wipers vertically, and at the conclusion of the impulse train when relay C releases, relay E then operates owing to the changeover at armature $da2$, and at armature $e1$, Fig. 4, connects up the rotary magnet $2RM$, at armature $e4$ connects earth to conductor 29 to operate relay C , Fig. 4, over its upper winding, and at armature $e5$ prepares a locking circuit for itself which becomes effective when relay C again operates. Upon the reception of the third digit the rotary magnet $2RM$ is responsive to advance the wipers into engagement with the desired line, and towards the end of the first rotary step the rotary off-normal springs are operated thereby at springs $2NR1$, Fig. 5, preparing a circuit to relay M and at springs $2NR2$ a circuit is prepared to relay CO , Fig. 4, which is however not effective on this type of call.

At the conclusion of the third series of impulses, relay L is again held operated and upon the release of relay C and during the slow release period of relay E , a circuit is completed for operating the switching relay $2H$ on its right-hand winding in series with the LK relay of the called subscriber's line circuit. Relay $2H$ then locks on its left-hand winding by way of the light armature $2h1$ in series with the upper winding of relay A which is not operated in this circuit owing to the high resistance of relay $2H$, at armature $2h2$ a point is opened in the circuit to the release magnet $2ZM$, at armature $2h3$, Fig. 4, relay CO is operated, at armature $2h4$ the impulsion circuit is opened to the driving magnets of this switch and at armatures $2h5$, $2h6$ and $2h7$ the connection is extended to the called subscriber's line circuit in readiness for the transmission of ringing current.

Relay CO it should be explained locks for the remainder of the call by way of its armature $co1$, at armature $co3$, Fig. 5, connects earth by way of the resting armature $da6$ to the common start lead TPS extending to the ringing tone and pulse supply equipment shown in Figs. 11 and 12, and moreover at armatures $co5$ and $co6$ completes still further points in the ringing circuit to the desired subscriber.

If the called party's line terminates on contacts situated in one of the lower 7 levels, standard ringing will be connected to his line from the terminal $CDR1$ corresponding to that shown in Fig. 12, by way of the resting normal post springs NP and the winding of the ring-trip relay F

to the upper speaking conductor and the called subscriber's instrument from whence a return circuit is completed over the lower speaking conductor to ring-return battery by way of the resistance connected to the resting armature *j5*. In order to inform the calling subscriber that the call is proceeding satisfactorily a leak on the main ringing circuit is provided by way of the operated armature *co4*, off-normal springs *2N3* and condenser *QD* to the upper speaking conductor on the calling side of the circuit, and has the effect of producing a tone in the calling subscriber's receiver characteristic of the ringing periods. If, however, the called subscriber's line 10 terminated on contacts situated on one of the upper three levels, ringing is then picked up from the bank contacts by way of wiper positive *2* and extended over the normal post springs *NP* which are operated on these levels to the winding of the ring-trip relay *F*. The type of ringing extended now depends on whether the called subscriber has an individual line or whether he is situated on a party line. In the former case wiper positive *2* will rest on a contact to which 15 is connected standard ringing such as is connected up by way of the resting normal post springs, while in the latter case wiper positive *2* will pick up the required code ringing from one of the terminals *CDR1* to *CDR10* shown in Fig. 12. All party line subscribers are allocated a separate directory number and those which represent the same party line are multiplied together on the bank. Thus assuming that on level 9 subscribers 91—93—94—95 and 97 are situated on 20 the same party line while the remainder of the subscribers on this level have individual lines, then the negative, positive and *P1* contacts of the party line numbers will be connected together, while the corresponding contacts in the bank associated with wiper positive *2* will be connected to different code ringing terminals such as for example *CDR1* to *CDR5* shown in Fig. 12. Similarly the contacts in the bank associated with wiper positive *2* corresponding to the individual subscribers numbers 92—96—98—99 and 90 will be 25 connected together and extended to the standard ringing terminal chosen, in this case assumed to be *CDR1*. It will now be convenient to describe the manner in which the various tones, time and meter pulses and code ringing signals are produced, for which purpose reference will now be had to Figs. 11 and 12. The equipment shown in these figures is common to the exchange and when any portion 30 of the exchange equipment requires either tones, pulse supply or code ringing, earth is connected to the common lead *TPS* shown extending from Fig. 11 to bring about the operation of the start relay *MS*. Relay *MS* at armature *ms1* completes an energizing circuit for the coil of the vibrator *VIB* which comprises a pendulum member supported on a spring reed and arranged to oscillate so as to alternately close the contacts *vib*. Upon the initial energization of the vibrator coil the pendulum member is drawn over to its right-hand position where the contacts *vib* close and complete a circuit for relay *P* which operates and at armature *p1* opens the energizing circuit to the vibrator coil so that the pendulum member swings 35 away from the pole pieces to close the left-hand contacts *vib*. In this manner the pendulum member is caused to oscillate and the movement is maintained indefinitely so long as the circuit is closed by the interacting effect of relay *P*. Connected in circuit with the vibrator contacts 40 is the split winding of a transformer *XFR* connected to battery at its mid-point by way of the impedance *I*. Each half of the transformer winding is energized alternately and in opposite polarity from the oscillating vibrator contacts and by induction into the secondary winding the two half waves are combined to form alternating ringing current which is smoothed to some extent by the presence of the condensers *QA* and *QB* connected to earth by way of resistance. 45 An alternating current relay *AC* is connected to the output terminal of the secondary winding of the transformer and as soon as the alternating current is generated this relay operates, and at armature *ac1* transfers the energizing circuit for the vibrator coil to earth by way of a comparatively high resistance, which has the effect of reducing the current to a value sufficient to maintain smooth vibratory motion of the pendulum, without undue hammering on the pole pieces of the coil. The alternating current relay *AC* is of the usual type used in telephone systems connected in bridge with a metal rectifier *MRC*, and its function is now generally well recognized. The current interruptions in the primary winding 50 of the transformer *XFR* are also used to provide dial tone, which is extended by way of the armature *p2* and condenser *QG* to the feed terminal *DT*. Busy tone is generated by relay *1BR* which is connected up at armature *ms2* and arranged to 55 energize in a self-interrupted circuit that is to say, on the opening of the armature *1br1* a high resistance is inserted in series with the energizing coil which reduces the current below the operating value of the relay so that it releases, and again becomes energized in series with its armature *1br1*. In this manner a buzzing operation of approximately 400 cycles per second is produced and by induction a tone is generated in the low resistance upper winding corresponding to 60 number unobtainable tone and extended by way of the condenser *QE* to the feed terminal *NU*. The operation of armature *ms2* also completes a circuit for relay *IR* which in turn at armature *ir1* energizes the driving magnet *INM* of the interrupter switch. It should be explained that the interrupter switch comprises a rotary switch driving mechanism, in which the usual banks and wipers are replaced by a set of cams designated in the drawings *INT1* to *INT4*, employed for interrupting the tone circuits and for producing a time pulse to operate delay sets in the exchange equipment. Relay *IR* is arranged to interact with the driving magnet *INM* so that the movement is continuous so long as the start relay is 65 operated, and the interacting operation is slowed down to some extent by the presence of the slug on relay *1R* which reduces the speed of operation to about .18 seconds for each cycle, and as 50 steps are required to turn the cams through one revolution the time occupied is therefore approximately 70 75 seconds. Referring to the timing cams *INT1* and *INT2*, it will be appreciated that earth is momentarily connected to the common conductor *FDS* and approximately 9 seconds later earth is 80 momentarily connected to the common conductor *FDZ*. Springs controlled by the cam *INT3* which produce an interruption of .75 seconds on and .75 seconds off are introduced into a parallel feed 85 from the *NU* tone supply which extends by way of the condenser *QF* to the terminal *BT* to provide a busy tone feed. The springs associated with cam *INT4* which produce an interruption of .2 seconds on and .2 90

seconds off are introduced into the circuit of the driving magnet CRM of the code ringing switch CRS, Fig. 12. Continuous ringing is extended from the secondary winding of the transformer over conductor 30 to the wipers 1b to 5b of the code ringing switch CRS, the bank contacts of which are connected together to produce the required ringing codes such as indicated diagrammatically in the drawings by long and short dashes opposite the feed terminals CDR1 to CDR10. As the driving magnet of this switch is being energized from an earth pulse of .2 seconds on and .2 seconds off it will be appreciated that the wipers rest on the contacts for .4 of a second, and from a consideration of the wiring, it will be seen that the short ringing periods have a duration of .4 of a second, while the long periods will have a duration of 1.2 seconds.

When the wipers of the code ringing switch come to the end of the code ringing cycle, wiper 6b leaves the first set of common contacts and engages the second set thereby completing a self-interrupted circuit to the magnet to drive the wipers to the home position whereupon the cycle again commences under the control of the interrupter cam INT4.

A meter pulse timing switch MPS is also provided for the purpose of supplying zone metering pulses to the exchange equipment, and is controlled from the armature i_1 , Fig. 11. Relay IR as already explained is interacting with the driving magnet of the interrupter switch at a cycle speed of approximately 1.8 of a second, and it therefore follows that the wipers of the switch MPS will rest on each contact for an equivalent period. In addition to the actual zone meter pulses which effect the operation of the calling subscriber's meter this switch also controls the application of timing pulses to the meter delay set, and for this purpose when wiper 1c of the switch encounters the second bank contact earth is connected to the common pulse lead MPS, and after a short delay period sufficient to prove the positive operation of the metering relay in the exchange equipment, earth is then extended over the common conductor MPZ, to cause the metering operation to commence. Moreover, as the MPZ lead is commoned over a number of contacts in the bank it will be seen that this pulse persists throughout the whole metering period. At the completion of the metering pulse cycle, wiper 6c leaves the first common set of contacts and engages the second common set from which a self-interrupted circuit is completed to the driving magnet MPM to restore the wipers to their starting position, from which they may then start out on another metering cycle providing that the start relay MS is maintained operated from other circuits.

Returning now to the operation of the switch shown in Figs. 4 and 5 when the calling subscriber removes his receiver to answer the ringing signal, a direct current circuit is provided by way of his instrument to enable relay F to operate over its right-hand winding from battery superimposed on the ringing circuit, and in opening its armature f_1 the short-circuit is removed from its left-hand winding over which the relay fully operates and locks for the remainder of the call. Relay F at armatures f_4 and f_5 completes the transmission circuit between the calling and called subscribers and relay I which functions as a battery feed to the called subscriber operates over the line in series with his instrument circuit and at armatures i_1 and i_2 reverses the battery over

the calling side of the circuit to the distant calling exchange for metering or supervisory purposes. Relay I moreover at armature i_3 completes a circuit to the shunt field relay D so that it operates on both its windings in series, thereby connecting up the meter delay set comprising relays DS and DZ. In accordance with circuit operations which will be fully described later, a metering pulse is extended over the meter lead 31 extending by way of the line finder which is without effect since the line circuits terminating both-way junctions are not equipped with meters.

In the event of the called party proving busy the testing wiper P1 encounters guarding earth instead of battery on the associated contact which prevents the operation of the switching relay 2H, and upon the release of relay E after its slow period, relay M then operates over its upper winding from earth at the resting armature 2h2, Fig. 5, armature rc_1 , off-normal springs 2N2, armatures b_2 and l_3 , rotary off-normal springs 2NR1, armature e_2 , upper winding of relay M to battery. Relay M thereupon locks for the remainder of the call by way of its armature m_1 to earth on the release trunk conductor, at armature m_2 connects earth to the common start conductor TPS, to set in operation the tone equipment shown in Figs. 11 and 12, at armature m_3 effects the application of busy tone from the terminal BT corresponding to that shown in Fig. 11, to the upper speaking conductor and the calling subscriber, at armature m_4 , Fig. 4, interrupted earth is connected to the individual supervisory lamp LP which flashes to indicate the busy holding condition, at armature m_5 the impulsing circuit is opened to the rotary magnet 2RM and at armature m_6 an alternative holding circuit is completed to relay LO. In this manner the calling subscriber is informed that the desired subscriber is unavailable, and the conditions described are maintained until the circuit is cleared from the distant exchange, whereupon relay L releases and this is followed shortly afterwards by relay B which energizes the release magnet ZM to restore the shaft and wipers to normal. Relay BB, however, remains held for a short period after the release of relay B to guard the circuit by maintaining earth on the release trunk conductor 21 and holds operated relay LO to disconnect the idle marking battery to the register translator group. Upon the release of relay BB earth is removed from the release trunk conductor so that the switching relay 1H in the finder and relay LK in the line circuit are released and the following circuit may now be traced for effecting the energization of the finder release magnet in order that the wipers may be restored to the normal position; earth on the contacts associated with armature l_1 , Fig. 4, armatures ba_2 and bb_2 , finder release conductor 20, armature 1h2, Fig. 2, off-normal springs 1N1, winding of release magnet ZM to battery. All apparatus is now restored to the normal position.

Considering now the case of a local subscriber desiring a local connection it is necessary for this purpose to take into use a register controller. Moreover as the local calling subscriber is likely to be one of three types that is, party line, coin-box or ordinary, it is necessary on at least two of these types of connection to extend a discriminating signal to the register controller taken into use, in order to prepare it for the transmission of a translated code corresponding to the class of subscriber who has originated the call. For this purpose party line subscribers and coin-

box subscribers are situated on levels 9 and 0 respectively of the line finder multiple and whenever these levels are selected by a finder the necessary discriminating signal is extended forward 5 to the register controller by way of the vertical bank and wiper. The operation of the switch shown in Figs. 4 and 5 is similar to that already described in connection with an incoming call from a distant exchange, in that when the calling line 10 is extended by way of the finder, relay L, Fig. 4, operates and in turn energizes relays B, BB and C to prepare the circuit for the reception of the impulses, but since the finder will have switched through on a level other than the first, which 15 it will be remembered was allocated for incoming calls only, a discriminating signal is not sent forward over conductor 28 and therefore relay LO, Fig. 4, remains in its normal position. In consequence therefore, when relay B operates at 20 armature b_3 , idle marking battery is extended over conductor 32 to mark a characteristic contact in the multiple banks of a group of selector finders such as SFS shown in Figs. 6 and 7, one of which is associated with each register controller. Upon the operation of relay BB at armature bb_4 earth is connected by way of the resting armatures lo_1 and ba_1 to the common start conductor 33 which extends to the register controller distributor circuit shown in Fig. 25 10. For convenience in the drawings this lead is not shown as continuous but is terminated in either figure on terminal points which bear the same designation.

It will now be convenient to describe the operation of the register controller distributor circuit, the function of which is to preselect an idle register controller and thereafter to connect with each register controller in turn in order that the load shall be evenly distributed. Although not 40 shown in the drawings an auxiliary distributor circuit is provided, arranged to be brought into service when the regular distributor fails or becomes associated with a faulty register controller.

Considering now the circuit details and assuming for the purposes of the description that at this instant the wipers of the distributor switch RDS, Fig. 10, are stood on contacts associated with a register controller which is already in use, wiper $4e$ will encounter earth over conductor 34 connected up by the operation of the switching relay KB in the register controller, Fig. 6, or alternatively by the operation of the springs 2BK of the busy key which is provided 50 for the purpose of artificially busying the register controller in the case of a fault or during test conditions. A circuit is now complete by way of wiper $4e$ of the switch RDS, Fig. 10, for operating the interrupter relay 3G, in series with the low resistance left-hand winding of relay K which remains inoperative owing to the high resistance winding of relay 3G. Relay 3G at armature $3g_1$ energizes the driving magnet RDM of the switch RDS which prepares for the advancement of the wipers on to the next set of contacts and at the conclusion of the magnet stroke the associated springs rdm are operated thereby opening the circuit of relay 3G which releases and in turn de-energizes the driving magnet RDM to enable the wipers to be moved on to the next set of bank contacts. In this manner an alternate action takes place between relay 3G and the magnet until the wipers of the switch RDS come into engagement with contacts 70 extending to a free register controller as indicated by the presence of marking battery encountered over wiper $4e$. To prevent the continuous rotation of the distributor switch wipers in the event of all register controllers being taken into use, one of the contacts associated with wiper $4e$ shown in the drawings as contact 22 is wired out to a busy common lead 35 which connects with the back contact in parallel of KA relays in all register controllers in the group. Consequently when all register controllers are taken into use at the same instant, all KA relays will be operated and earth is removed from the busy common lead 35 to arrest the wipers of the distributor switch RDS in this position. No further circuit operations take place until a call is originated in the manner described, and by the operation of the start relay ST, at armature st_1 earth is connected to the common start conductor TPS extending to the tone and timing equipment in Figs. 11 and 12, at armature st_2 the alarm relay 1TA is connected in a circuit with the pulse conductor FDS also extending to Fig. 11 and at armature st_4 the switching relay K is operated on both its windings in series from earth on the busy common 35 to idle marking 100 battery connected up over wiper $4e$, which is of low resistance to short-circuit the interrupter relay 3G against operation at this time. Relay K in operating at armature k_1 completes a locking circuit for itself over its left-hand winding 105 which is sufficiently low in resistance to guard the register controller from further selection, at armatures k_2 , k_3 and k_4 prepares a circuit for the subsequent interaction of relay 3G with the driving magnet of the selector finder, and at 110 armatures k_5 and k_6 transfers the alarm circuit to the other alarm relay 1TB since it is now proved that the distributor circuit has completed its switching function satisfactorily and the fault, if any, must now lie in the register controller.

It will be remembered from the foregoing description that the selector requiring connection to a register controller is marked by battery in the multiple of the selector finders such as SFS, and assuming for the purpose of the description that the wipers of the selector finder switch taken into use are resting on contacts other than those marked, wiper $8d$ will encounter a disconnection 120 and the following circuit then becomes effective 125 in operating relay 3G of the distributor in series with relay KA of the register controller: earth at armature k_4 , Fig. 10, wiper $3e$ and bank contact, conductor 36, right-hand winding of relay KA, armature ka_1 , interrupter springs sfm associated with the driving magnet of the switch SFS, conductor 37, bank contact and wiper $2e$ of the distributor switch RDS, Fig. 7, armature k_3 , winding of relay 3G to battery. Relay 3G at armature $3g_1$ extends earth by way of wiper $1e$ and conductor 38 to energize the driving magnet SFM of the sender finder switch to prepare for the advancement of the wipers into their next position and at the conclusion of the magnet stroke, the interrupter springs sfm open the circuit to relay 3G which releases and in turn de-energizes the driving magnet SFM to enable the mechanical movement of the wipers to take place. In this manner relay 3G is now caused to interact with 130 the driving magnet of the selector finder switch in order that the wipers shall be moved into engagement with the selector requiring connection. When the marked position is reached wiper $8d$ of the switch SFS encounters idle marking bat- 150

tery over conductor 32 from the selector, which is of low resistance to short-circuit the interrup-
5 ter relay 3G thereby terminating the hunting operation, and the current in the circuit of relay KA is now increased sufficiently to enable it to operate over both its windings in series. Relay KA locks on its left-hand winding which is of low resistance and shunts the idle marking battery to such an extent as to prevent another reg-
10 ister controller from switching in on to the same selector. Relay KA at armatures *k2*, *k3*, *k4*, *k5* and *k6* extends the register controller by way of the wipers of the switch SFS to the calling selector and at armature *ka7* operates relay KB, Fig. 6, which at armature *kb1* connects direct earth instead of marking battery to the test contact associated with wiper *4e* of the distributor switch RDS. This connection short-circuits relay K in the distributor circuit so that it releases to enable relay 1G to interact with the driving magnet RDM to move the wipers into engagement with the next idle register controller. This feature is effective even though the start relay ST remains operated from calls originated 25 simultaneously so that under all conditions the distributor switch RDS is caused to search for another register controller.

In case a fault occurs in the distributor circuit which prevents relay K switching to a free register controller relay 1TA is operated from the earth pulse extended over conductor FDS from the time pulse equipment so that it locks on its other winding by way of armature *1ta1* and at armature *1ta2* connects relay 1TC in circuit with 30 the other time pulse conductor FDZ. If the fault persists for the full period for which the timing device is set, namely in this instance 9 seconds, an earth pulse is extended over the conductor FDZ to operate relay 1TC which thereupon locks 35 over its right-hand winding to earth on the common conductor 39 extending to an alarm reset key not shown. The locking circuit of relay 1TC it will be noticed extends by way of a resting armature of relay 1TC of the other distributor circuit which is shown as enclosed in a dotted rectangle to indicate its remote association. Relay 40 1TC moreover at armature *1tc3* connects earth to a common conductor 40 extending to a main alarm circuit which may be of any well-known type and at armature *1tc5* transfers the incoming start conductor 33 to conductor 41 extending to the start relay ST of the other distributor circuit, so that all calls originated during this 45 period will be completed over the second distributor circuit.

In case a fault occurs in the register controller which prevents it from switching in on the selector requiring connection, relay K of the distributor will have operated under these conditions and upon the reception of the earth pulse over the conductor FDS relay 1TB is operated and locked, and at armature *1tb2* again prepares the circuit for relay 1TC to the pulse conductor FDZ. If the fault persists for the full period, 50 upon the connection of earth to the conductor FDZ relay 1TC is again operated and locked to fulfil the functions already explained, and in addition since relay 1TB is operated at this time, earth is extended by way of the wiper *4e* to mark 55 the faulty register controller as busy in order to prevent the second distributor switch from becoming associated therewith.

Returning now to the register controller and assuming that the call in question is proceeding 75 satisfactorily upon the operation of relay KB at

armature *kb2*, Fig. 7, a circuit is completed to the impulser IP which is provided one per register controller and comprises a pendulum vibrator mechanism arranged to operate two sets of impulsive springs designated in the drawings OPS 80 and SPS, Fig. 7. Springs OPS are included in the line circuit, for delivering trains of impulses to the automatic switches, while springs SPS are arranged to control the stepping of what is known as the sender switch which serves to count off the required trains of impulses in accordance with markings made on its bank contacts; at armature *kb2* earth is connected to the common start lead TPS extending to the timing and tone equipment shown in Figs. 11 and 12 and at armature *kb5*, Fig. 7, earth is connected to the holding conductor 42.

Consequent upon the switching through of the register controller relay A, Fig. 5, of the calling selector is operated over the circuit: earth via the lower winding of relay A, armature *2h6*, conductor 43, bank contact and wiper *2d* of the switch SFS, Fig. 7, armatures *ka3*, *bp6*, *1m4* and *ka2*, wiper *1d* and bank contact of the switch SFS, conductor 44, armatures *2h5* and *c4*, winding of relay A to battery. Relay A in operating its armature *a1*, Fig. 4, completes a circuit for operating relay BA which locks by way of its armature *ba1* at the same time opening the start circuit traced over conductor 33 to the distributor switch, at armature *ba2*, same figure, transfers the impulsive circuit for the driving magnets of this switch to the control of relay A, and at armature *ba3* connects earth to the release trunk conductor 21. The circuit is now in a condition to respond to the dialled impulses and in order that the calling subscriber shall be signalled to this effect, dialling tone is extended from the register controller over a circuit which may be traced from the feed terminal DT, Fig. 6, extending from Fig. 11 of the tone equipment, condenser 45, armature *1m6*, *bp5* and *ka6*, wiper *6d* and bank contact of the switch SFS, conductor 46, off-normal springs 2N3, Fig. 5, low capacity condenser QD to the upper speaking conductor extending to the calling subscriber's instrument.

Generally the operation of the register controller is already well-known in essentials and a full description of the operation of a similar register controller is given for instance in U. S. Patent No. 1,901,156, granted March 14, 1933, so that a brief description only is given of the main switching features without reference to detailed circuits. It will be sufficient to say that 120 when the calling subscriber operates the dial to deliver the first digit of the six which are necessary with the particular numbering scheme under consideration, relay L in the selector, Fig. 4, responds and repeats these impulses to the vertical magnet BCV of the two-directional BC switch designated BCS in Fig. 8. Relay 1C which is of low resistance is operated continuously during the train of impulses and completes the circuit to the driving magnet UDM of the units 125 storing switch U, and at the conclusion of impulsive when relay 1C releases the driving magnet UDM is de-energized to advance the wipers of the units switch into their second position 130 where they connect up the rotary magnet BCR 135 of the BC switch. The second train of impulses are therefore effective in setting the wipers of the BC switch into engagement with a particular set of contacts from which a code may be 140 set up in accordance with the cross connec- 145 150

tions on the translating field to the bank of the 5 sender switch SND, Fig. 9. The third, fourth, fifth and sixth digits corresponding to the thousands, hundreds, tens and units figures of the number dialled are received on single motion storing switches TH, HU, T and U respectively, the driving magnets of which are shown in Fig. 6, while it will be realized that the switch U serves as a digit distributor until the reception of the 10 final digit, which is stored by an equivalent displacement of its wipers over the bank contacts.

As soon as the wipers of the switch BCS are 15 completely set, the wipers of the units switch move into their third position and assuming that relay LO is normal, as it will be if the call is other than local, or for the adjacent main exchange, earth is connected to the lower side of 20 relay 1G, Fig. 7, which operates when the impulsing springs SPS open and completes the driving circuit to the magnet SNM of the sender switch SND which thereupon rotates its wipers in search of the marking made on bank 4f by way of wiper 2e of the control switch CNT in its first position. Trains of impulses are 25 delivered by way of the impulsing springs OPS, Fig. 7, to set the automatic switches, while the control switch CNT is arranged to advance one step between each train so as to connect up the appropriate wipers of the BC switch, and later 30 the numerical storing switches from which markings are made in accordance with the cross connections on the translating field.

When all digits have been delivered by the 35 register controller wiper 2e of the control switch will have moved to its 10th position where earth is connected to the terminal point CO corresponding to that associated with wiper 7d of the selector finder switch SFS, Fig. 6, and from thence is extended over conductor 47 to operate relay CO in the selector Fig. 4. Relay CO 40 locks by way of armature co1 to earth over conductor 48 from the operated armature 2h2 of the switching relay, at armature co2 disconnects the idle marking battery from conductor 32 thereupon releasing relay KA which in turn dissociates 45 the register controller from the wipers of the switch SFS and releases relay KB to remove earth from the common holding conductor 41 so that all apparatus in the register controller is 50 now restored to normal. The other functions performed by the armatures of relay CO will be readily appreciated from the description already given of an incoming call.

In order to take care of the case in which a 55 spare or unallotted code is inadvertently dialled by the subscriber, the switch BCS is provided with a bank arc of the so-called P. B. X. type indicated in Fig. 7, which comprise a semi-cylindrical metal plate provided with 10 rows each of 10 holes into 60 which screws can be inserted so as to contact with a special wiper carried by the shaft. Such screws are provided in all positions of the switch BCS which do not correspond to a regular code and consequently if the switch BCS is set by dialling 65 to such a position a circuit is completed for relay 1M which locks by way of its armature 1m1 and at armature 1m3, Fig. 6, prepares for the connection of earth to the forced release conductor extending over wiper 6d and bank contact of the 70 switch SFS. As already explained at the conclusion of the setting operation of the switch BCS the sender switch SND commences to rotate to deliver the translated code, but owing to the opening of the impulsing circuit at armature 1m4, 75 Fig. 7, the train of impulses delivered in respect

of the first routing digit is not effective. Upon the operation of relay SZ under these conditions, when the sender switch locates the first marked position earth is connected by way of armature sz3, Fig. 6, armatures 1m3 and ka6, wiper 6d and bank contact over the forced release conductor 46 to operate relay M in the selector. Relay M locks to earth on the release trunk conductor, at armature m6 closes a circuit for relay LO which operates and disconnects earth from the start conductor 33 and removes the idle marking battery from conductor 32 in order that the register controller shall be restored to normal, and moreover at armature m3, Fig. 5, connects number unobtainable tone from the terminal point NU and the operated off-normal springs 2N3 to the calling subscriber to indicate that the number called is unavailable. It is of course necessary for the completion of the tone circuit that the wipers of the selector switch shall be moved from their normal position to operate the off-normal springs, and although the switch is not responsive to impulses delivered from the register controller, the opening of the impulsing circuit releases relay A and by this means a single impulse is delivered 100 to the vertical magnet 2VM to raise the shaft and wipers to the first level.

If the subscriber fails to dial any digits within a predetermined interval, the register controller is again forcibly disconnected and this is brought about by a time pulse circuit which involves the operation of relays TP and 1M, Fig. 7. Relay TP is operated from an earth pulse on the conductor FDS from the timing and tone equipment, so that it locks on its other winding and connects one winding of relay 1M in circuit with the other pulse conductor FDZ, and upon the connection of earth to this second conductor after the timing period has elapsed relay 1M again operates to fulfill the functions already described. Similarly 115 if the subscriber dials one or more digits, but less than the number required to enable the register controller to release in the normal manner, relays TP and 1M will again be operated from the time pulse circuit in order that NU tone may be delivered 120 to the calling subscriber.

It will be noticed from the drawings that an armature of relay 1C which is operated for each train of impulses delivered to the register controller is included in the locking circuit to relay 125 TP and has the effect of releasing this relay during the normal progress of the call in case it should become operated from earth over the time pulse lead.

In case the subscriber should dial before the 130 reception of dial tone, that is before connection is established with a free register controller, relay M is operated when the wipers of the selector switch move from their normal position to deliver NU tone to the calling subscriber, and at the 135 same time relay LO is operated to remove earth from the register controller start lead 33.

It has previously been explained that both the 140 rural and main exchanges have the same exchange code and the discrimination as to the destination of the call is effected in accordance with the first numerical digit stored in the register controller. With the particular arrangements shown five is chosen as the deciding digit for local office calls.

The operation of the register controller for this 145 feature is much the same as that already described with the exception that at the conclusion of the setting of the BC switch relay 1LO, Fig. 9, is operated from wiper 1a of the BC switch over 150

a suitable connection on the translating field and immediately locks by way of its armature $1lo1$ to earth on the common holding conductor 41. Relay 1LO moreover at armature $1lo2$, Fig. 7, opens the start circuit to the sender switch SND so that the transmission of the translated code is temporarily suspended, at armature $1lo3$ associated with the bank $3k$ of the thousands storing switch TH a circuit is prepared to the terminal point LO and at armature $1lo4$, Fig. 8, a digit marking is made to the translating field in case the call in question is intended for the main exchange.

It will be appreciated that such an arrangement is necessary since the normal marking circuit by way of wiper $1a$ of the switch BCS is employed under these circumstances for operating the discriminating relay 1LO.

If now the next digit dialled is 5 indicating that the call is local the wipers of the thousands storing switch TH will be moved into their 6th position, and at the conclusion of impulsing when the wipers of the units distributor switch advance into their third position earth is extended from the common holding conductor 41 by way of wiper $2c$ and bank commoning of the units switch U and wiper $3k$ and sixth bank contact of the thousands switch TH, operated armature $1lo3$ to terminal point LO corresponding to that associated with wiper $7d$ of the switch SFS, Fig. 6, conductor 47 extending to the selector, winding of relay LO, Fig. 4, to battery. As already explained relay LO in operating transforms the selector switch into a final selector and at the same time opens the holding circuit to the register controller which thereupon restores to normal. The remaining three digits of the number are now received direct on the final selector which functions in an exactly similar manner to that already described for an incoming call. The fourth digit of the local number which is always 7 is absorbed and relay DA operates to establish connection with the upper set of wipers and also prepares for the application of a single pulse to the metering conductor 31.

The ringing of the called subscriber and the switching through of the speaking circuit when he replies takes place in the manner already described for the incoming call and upon the operation of relay I and in turn relay D over both its windings in series, the meter delay relays DS and DZ are brought into operation. Upon the operation of armature $d1$ the right-hand winding of relay DS is connected in circuit with the time pulse conductor MPS extending to the meter pulse timing switch in Fig. 12 and upon the extension of an earth impulse over this lead relay DS is operated and locked on its left-hand winding, at armature $ds2$ connects its centre winding in series with the lower winding of relay DZ to the other time pulse conductor MPZ, and at armature $ds4$ prepares an alternative circuit to the start conductor TPS which also extends to the tone and timing equipment. After a suitable delay period has elapsed, sufficient to ensure the positive operation of the metering relay D an earth pulse is delivered over the time pulse conductor MPZ thereby operating relay DZ in series with relay DS which holds. It will be realized that in case the metering relay D is only momentarily operated, which might possibly be the case from inductive surges in the line, the holding circuit for relay DS will be opened so that it releases and therefore relay DZ is not operated to apply the metering potential to the meter lead 31. Relay DZ in operating at arm-

ture $d21$ removes the short-circuit from its upper winding so that it holds for the remainder of the call in series with the switching relay 2H. At armature $d22$ relay DZ opens the initial energizing circuit to relay DS so that it shall not again be operated during this call, at armature $d23$ opens the locking circuit to relay DS, at armature $d24$ completes the metering circuit over conductor 31 to the calling subscriber's meter MTR, Fig. 1, at armature $d25$ prepares a circuit to the supervisory lamp LP and at armature $d26$ opens the point in the circuit to the common start conductor TPS.

As already explained in connection with the tone and timing equipment the earth pulse connected to the common conductor MPZ persists for the duration of the metering condition which may at the maximum be equivalent to the separate application of six metering pulses to the metering conductor, and at the end of the full cycle when earth is removed from the conductor MPZ relay DS releases to open the metering circuit and also the circuit to the start lead TPS, but relay DZ remains operated for the remainder of the connection to ensure that further metering will not take place.

Returning again to the register controller and assuming that the third digit dialled by the subscriber is 6 corresponding to a call for the main exchange, the wipers of the thousands counting switch TH will be advanced to their 7th position, and when the units distributor switch U advances to its 4th position at the conclusion of impulsing, a circuit is completed by way of the wipers $2c$ of the switch U and $3k$ of the switch TH and bank commoning of both to relay IG which transfers the impulsing circuit to the driving magnet SNM of the sender switch. The register controller therefore commences to send out the translated code for the main exchange and the first digit delivered which is to determine the zone metering of the call is made in accordance with the marking on the sender switch bank $4f$ by way of the operated armature $1lo4$, which as previously explained takes the place of the marking wiper $1a$ of the BC switch which is used under these circumstances for another purpose. In accordance with the first series of impulses delivered from the register controller the selector switch wipers are set to the required level and depending upon the position of the vertical wiper $1vw$ one of the terminals MP1 to MP6 extending from the banks of the zone metering switch in Fig. 12 is connected to the metering circuit by way of the resting armature of relay DA which is operated only on local calls. As already explained all outgoing calls may be considered as extending over junction lines to the main exchange. Ten junction lines are provided and it will be appreciated, therefore, with the particular method of zone metering discrimination employed, that it is necessary for the same junctions to be selected over any one of 6 levels depending upon the position of the vertical wiper, and consequently each junction must make six appearances in the bank. For this purpose the first contacts of the lower 6 levels will be commoned vertically and connected to junction 1, the second contacts will be commoned vertically and connected to junction 2 and so on in respect of the remaining 8 sets of contacts so that the same junctions are accessible over different levels as determined by the zone metering registration necessary for the desired exchange.

Returning again to the detailed circuit operations upon the transmission of the first translated series of impulses from the register controller relay A in the selector is impulsed in synchronism, and at its armature a_1 repeats these impulses to the vertical magnet 2VM in series with the low resistance winding of relay C. At the end of the first series of impulses relay C releases after its slow period, since the initial energizing circuit is opened at the off-normal springs 2N1 and in turn opens the holding circuit for relay A at armature c_4 , Fig. 5. A circuit is now completed to the rotary magnet 2RM by means of which the wipers are advanced into engagement with the first set of contacts in the level selected. From this point the operation of the switch may be compared to that of an ordinary group selector in which relay A functions as the interrupter relay.

If the first junction tested proves busy wiper P2 will encounter guarding earth which serves to short-circuit the switching relay 2H against operation and when the interrupter springs 2rm of the rotary magnet close at the end of the mechanical stroke a circuit is again closed for relay A which operates and at armature a_1 opening the energizing circuit to the rotary magnet 2RM which releases. In this manner an alternate action takes place between relay A and the rotary magnet to effect the advancement of the wipers into engagement with the first available junction and when this is found wiper P2 no longer encounters earth and upon the closure of the springs 2rm a switching circuit is completed to relay 2H which operates in series with the upper winding of relay A. In addition to its usual function of switching the calling circuit through to the line selected, relay 2H under these conditions immediately closes a circuit for relay F since the switch is functioning as a selector and is not required to extend ringing current. The register controller continues with the transmission of the routing impulses and also the numerical impulses which are delivered unchanged, and these are extended over the junction circuit to set the switches in the distant office.

When all trains of impulses have been sent, the control switch in the register controller will come into its final position from which earth is connected to conductor 47 to operate relay CO in the selector, which in turn releases the register controller and switches the speaking circuit through to the junction selected in the manner previously described. Relay I is operated over the junction in series with the shunt-field relay D which is not operated at this time since the direction of current in the circuit is normal.

Ringing current is extended to the called subscriber's instrument by the final switch in the distant train and when he replies battery is reversed over the junction circuit to initiate the metering operation. Relay I remains operated under these conditions, but owing to the change in the direction of current the shunt field relay D is operated to connect up the meter delay set comprising relays DS and DZ. These relays are operated after a short period in the manner already described, and a series of battery impulses are connected to the metering lead 31 by way of the vertical wiper and bank depending upon the level on which the wipers are switched and serve to operate the calling subscriber's meter a number of times in order to assess the correct value of the call.

At the main exchange the junction terminates on a selector repeater which is guarded on release by the cumulative slow release period of two relays. Consequently in order to ensure the distant end of the junction is free before it is again taken into use at the rural exchange it is necessary that an additional period shall be provided in the selector and this is taken care of by the cumulative slow releasing periods of three relays B, BA and BB.

The operations so far described have dealt with the reception of incoming calls from a distant exchange and also calls originated by a local regular subscriber, and it has been mentioned in the case of calls originated by coin box and party line subscribers that a discriminating signal is in each case extended to the register controller to modify this operation since the facilities offered to such subscribers are of necessity somewhat restricted by the fact that neither are provided with automatic meters and the assessment of the call must therefore be under the control of an operator. To cater for this arrangement it is obviously necessary that the register controller shall be enabled to deliver different translations for the same number dialled, depending upon the classification of the calling party, and this is achieved by disposing of party lines on level 0 of the finder bank multiple, and coin box lines on level 9 of the finder bank multiple.

Consequently when a party line subscriber originates a call the finder taken into use will be raised to level 0 and upon the operation of the switching relay 1H earth is extended by way of the vertical wiper VW and bank contact over conductor 49PL by way of the bank and wiper 5d of the selector finder switch SFS, Fig. 6, of the register controller taken into use, to operate the discriminating relays PL and CB in series. Similarly in case a coin box subscriber originates a call the finder taken into use will be raised to the 9th level and earth is extended by way of the vertical wiper and conductor 50CB to operate the discriminating relay CB only in the register controller. It should be explained, however, in case of local calls that the operation of the discriminating relays PL and CB in the register controller are without effect, since as already described when the local discriminating digit 5 is dialled the wipers of the thousands counting switch are moved to a position from which earth is subsequently connected to the terminal point LO extending by way of the wiper 7 and bank contact of the switch SFS to operate relay LO in the selector. The selector is thereupon converted into a final selector and responds directly to the three remaining digits of the number the first of which is always 7 to enable the switch to perform its digit absorbing function. Relay LO in addition opens the holding circuit to the register controller which thereupon restores to normal. It will thus be appreciated insofar as local connections are concerned the facilities offered to coin-box and party-line subscribers are the same as those for the regular subscribers.

At this stage of the circuit operations it will be convenient to describe the revertive calling feature of the selector, whereby a party line subscriber is enabled to call another party line subscriber connected to the same line. Metering is, of course, unnecessary on this type of call and consequently the meter bank contacts of the 0 level are not multiplied together, and moreover those associated with party lines are connected back individually to the associated selector. In

140

145

150

the circuit shown three party lines comprising if necessary as many as 10 parties per line are assumed to be connected to the first three contacts of the 0 level. In order that the connections to the meter bank contacts may be clearly understood the first three contacts concerned are shown in detail to the right-hand side of Fig. 2 designated MOL1, 2 and 3, and since it is further assumed that the three groups of 10 party line subscribers concerned are connected to levels 0, 9 and 8 of the selector bank multiple then the meter bank contacts are wired to contacts 0, 9 and 8 on the vertical bank of the selector for the purpose of operating the revertive call relay RC in a manner which will now be described.

Considering now a party line subscriber calling another party line subscriber on the same line, this is effected by the dialling of the ordinary directory number and the operations which take place insofar as the taking of the register controller and its release after the reception of the discriminating digit is identical with that of the local call already explained. Since, however, the wipers of the selector switch are moved into engagement with the line which is already calling the switching relay 2H is prevented from operating and under normal circumstances when relay E released after its slow period relay M would operate to transmit the busy signal to the calling party. Under these circumstances, however, as the line connected with is a party line, wiper negative 2 encounters resistance battery which is multiplied to the corresponding contacts on all such party lines, and furthermore as it is assumed that the calling party has called its own party line then the vertical wiper of the selector will be in engagement with a contact connected to earth by way of the meter bank and wiper of the finder switch and, in consequence, the revertive calling relay RC in the selector is operated.

The detailed circuit may be traced from resistance battery encountered by the wiper negative 2 of the selector, conductor 51, armature c5, winding of relay RC, Fig. 4, armatures f2 and da8, vertical bank and wiper 1VV of the selector to meter contact MOL of the calling party's line, wiper M of the finder, armature 1h5, conductor 31 to earth at the resting armature da4 in the selector. Relay RC therefore operates before the release of relay E and at armature rc1 opens the circuit to relay M to prevent its operation, at armature rc2 prepares a circuit for operating the switching relay 2H, over its left-hand winding in series with relay A, at armature rc3 completes a circuit for holding relay BB, Fig. 5, and at armatures rc4 and rc5 disconnects points in the circuit to relay L which are without immediate effect.

Party line subscribers are instructed from the directory to replace the receiver after dialling a party on their own lines, and when this is done relay L releases and is followed shortly after by the guard relay B, and the connection is then held by the auxiliary guard relay BB, the circuit of which is maintained from an operated armature of relay RC. Relay B in releasing at armature b6 completes a circuit in conjunction with the operated armature rc2 for energizing the switching relay 2H on its left-hand winding in series with the upper winding of relay A. Relay 2H operates to extend the ringing circuit to the calling party's line, and as relay B has released meanwhile and relay RC remains held, the ringing current is without effect on relay L which is now completely disconnected from the line. The normal post springs NP are operated on this level

and therefore the type of ringing extended depends upon the selection which is made over wiper positive 2 and is supplied from one of the terminals CDR1 to CDR10, Fig. 12, of the code ringing switch CRS.

All subscribers to the party line connected with will now be rung with a characteristic code, including also the originating party and when the desired subscriber replies by removing his receiver from the switch-hook, relay F in the selector is tripped in the usual manner to cut off the ringing circuit, and is effective also under these circumstances in releasing the switching relay 2H and the revertive calling relay RC. Upon the release of relay RC, relay L is again connected to the line circuit so that it re-operates and brings up relay B to restore the selector switch to the speaking condition. Moreover the party who has originated the call on hearing the ringing cease is thus informed that the call has been answered and thereupon again removes his telephone from the switch-hook to commence the conversation. Battery feed to both parties is supplied by way of the windings of relay L which are, of course, high impedance to reduce the transmission loss.

Consideration will now be given to the transmission of a re-routing code from the register controller in response to a distant call by either a coin box or party line subscriber. The circuit operations involved are much the same as those described in our co-pending application No. 11974/31 in that the 6th bank and wiper of the BC switch is reserved exclusively for use in connection with re-routing codes. Similarly the sender switch is equipped with additional wipers and banks over which markings may be made to set the BC switch to a different position and in order that two positions may be marked for the same setting of the sender switch, two distinct sets of wipers and banks are provided, namely 5f, 6f and 7f and 8f in Figs. 8 and 9, either of which may be connected up depending upon whether the calling subscriber is coin box or party line.

In order that the re-routing arrangements may operate satisfactorily it is necessary that a fair proportion of the one hundred positions of the BC switch shall be available for setting up re-routing codes, and it will therefore be desirable before commencing the circuit description to outline the manner in which these positions may be obtained without embarrassment to the regular codes. The translation field for each register controller generally comprises a block of 100 horizontal rows of tag points, each row corresponding to a separate position of the BC switch wipers, for example, if the digits 65 are dialled the wipers will be positioned on contacts which are connected to tags in the 65th horizontal row in the translation field. Moreover as it is generally considered undesirable to employ the digit 1 as the first digit of a telephone number owing to the possibility of accidental preliminary impulses, no letters are included in the first finger hole of the dial, and it therefore follows that it will be impossible for the digit 1 to be employed for either of the routing digits. This will mean that the BC switch cannot be set by dialling to any set of contacts on its first level or similarly to the first contact of any of the other levels, and from this source alone it will be appreciated that there are 19 positions normally unused for regular codes. Further all positions in level 0 are unused for a similar reason since it is arranged for the manual board translation to

80

85

90

95

110

115

120

125

130

135

140

145

150

be delivered immediately on the reception of the digit 0, without the necessity for the wipers to be moved into engagement with the bank. Thus assuming that the BC switch bank is connected up to its full capacity for normal translated codes, there will always be at least 38 positions available for re-routing.

Considering now one typical row of tags in the translation field corresponding to a position of the BC switch, generally the first contact is allocated for spare code purposes, the following 6 are connected to the contacts in the bank of the BC switch connected with by the 6 wipers, two further tags are allocated respectively for digit 15 cut-off and full cut-off, while the remaining 10 are commoned vertically and connected to banks of the numerical switches and also the bank of the sender switch to provide for the digit markings. To set up a particular translation therefore, it remains for connecting straps to be inserted between the tags corresponding to the wiper positions, and the common set of 10 tags corresponding to the bank positions of the sender switch, while the cut-off terminals will be connected up to those contacts in respect of which a corresponding digit is not required. Since, however, as has already been explained, spare code positions are determined over the miniature P. B. X. bank arc, then the 100 spare code 30 tags normally provided in the translating field are not now required and are wired out to the 25 contacts in the bank 4f of the sender switch shown in Fig. 9 for another purpose, each contact making four appearances in the translating field.

Returning again to the circuit operation and assuming for the sake of example that a coin box subscriber originates a call. Immediately the register controller is taken into use relay CB, 40 Fig. 6, is operated over the bank and wiper 4d of the selector finder SFS in response to the discriminating signal extended from level 9 of the finder switch taken into use. Relay CB in operating at armature cb1, Fig. 8, disconnects 45 wiper 2e of the control switch CNT and establishes direct connection over conductor 52 with the re-routing wiper 6a of the BC switch BCS. Relay CB moreover at armature cb2, Fig. 7, short-circuits the impulsive springs OPS at armature 50 cb4 closes a circuit for relay BR, and at various other armatures which have no immediate effect prepares for the release and resetting of the BC switch to the re-routing position. In response to the routing digits and in a manner substantially as described above, the wipers of the BC switch are moved to a corresponding position, and assuming that the code dialled is other than local or for the adjacent exchange when the units switch moves into its third position earth 55 is connected by way of wiper 6a and bank contact of the BC switch to mark a position in the bank 4f of the sender switch SND, which is effected by strapping the tag on the translating field corresponding to wiper 6a, to a particular tag in the spare code set which are now wired out to the sender switch bank as already explained. Earth is also connected to one side of the relay 60 IG, Fig. 7, which operates and completes the driving circuit to the magnet SNM of the sender switch which hunts for the marked position.

When the marked position is found relay SZ 65 operates and locks to terminate the hunting operation but owing to the operation of relay CB meanwhile the homing circuit to the sending switch is opened and the wipers remain locked in

this position. Relay SZ moreover, in addition to fulfilling its usual functions opens the circuit to relay BR in Fig. 6, which releases after the expiration of its slow releasing period and completes a circuit for restoring the BC switch to its normal position. In case, however, on certain codes it is desired that the coin box subscriber shall take the same translation as the regular subscriber, it becomes necessary at this stage to cut-off the re-routing feature thus enabling the BC switch to be held in its original position. This case would arise for instance if the call was for a manual exchange when the call would in any case be dealt with by an operator. For this purpose the corresponding contacts in the bank 7f or 8f of the sender switch are wired out over conductor 53 to relay 2R, Fig. 7, which operates during the slow releasing period of relay BR in a circuit which may be traced from: earth connected to armature sz5, Fig. 7, conductor 54, armatures br2 and ar3, conductor 55, armature f2, Fig. 9, normal or operated depending upon whether the calling subscriber is coin box or party line, wiper and bank contact of the sending switch SND, conductor 53, winding of relay 2R, Fig. 7, to battery. 100 Relay 2R locks for the remainder of the connection to earth on the common holding conductor 41, at armature 2r4, Fig. 6, opens the circuit to the release magnet BCZ before the release of armature br3, and at armature 2r5, same figure, opens 105 the circuit of relay CB. The homing circuit is now completed to the sender switch SND at armature cb5, Fig. 7, so that it restores, while at armature cb1, Fig. 8, wiper 2e of the control switch CNT is again connected up and the register controller thereupon commences to deliver the regular code in the manner described for this type of call earlier in the description.

If, however, the coin-box subscriber dials a code which is not required to take the regular 115 routing, the corresponding contacts in the bank of the sender switch previously referred to are not wired out to relay R and consequently upon the release of relay BR the release magnet BCZ is energized to restore the BC switch to the normal 120 position. When the normal position is reached the off-normal springs are restored and at springs 3N1 relay BR re-operates over its left-hand winding and is followed by the operation of relay AR which locks over its armature ar1, at armature 125 ar2, Fig. 7, operates relay 2R and at armatures ar3, Fig. 8, and ar4, Fig. 6, prepares a circuit for resetting the wipers of the BC switch vertically to the position selected over wiper 5f of the sender switch.

In the drawings the re-routing positions for coin box subscribers are shown as located along level 1 of the BC switch, while the re-routing positions for party line subscribers appear in level 0. Relay 2R is operated at this period for 135 a different purpose, namely, the disconnection of the wiper of the miniature P. B. X. bank arc, since it will be realized that the wipers of the BC switch are now required to position themselves on contacts which appear to regular subscribers as 140 spare codes. Furthermore at armature 2r4, Fig. 6, an energizing circuit is completed for the vertical magnet BCV of the BC switch in series with the low resistance right-hand winding of relay 145 BR. It will be noted that relay CB is not released under these conditions owing to its circuit being maintained by way of the operated armature ar5. The wipers of the BC switch are therefore raised to the first level and at the conclusion of the 150

magnet stroke the springs *bcv*, Fig. 8, are closed to complete a circuit to the interrupter relay 2G which prepares a locking circuit for itself at armature 2*g1*, and at armature 2*g2* opens the energizing circuit for the vertical magnet. In this manner an alternate action takes place between relay 2G and the vertical magnet BCV in order that the wipers may be raised to the marked level. At the conclusion of the first vertical step the off-normal springs are again operated, thereby opening the initial energizing circuit to relay BR which is not released but remains operated during the vertical setting owing to the inclusion of its low resistance winding in the magnet circuit.

When the wipers of the BC switch are raised to the marked level, relay 2G then locks over its lower winding to earth encountered by the vertical wiper BCVW over the banks and wipers of the sender switch and after a short interval relay BR releases to transfer the driving circuit to the rotary magnet BCR and at armature *b7s* opens the locking circuit to relay G and connects the winding to wiper *7f* of the sender switch to prepare a circuit for terminating the automatic rotary movement. Upon the release of relay 2G a circuit is completed to the rotary magnet BCR which thereupon interacts with relay 2G to advance the wipers of the BC switch into their rotary position, and in a manner similar to that described in connection with relay BR it will be seen that relay AR is held operated during the setting period.

When the marked rotary position is found as indicated by the selection over wiper *7f*, relay 2G is again locked over its lower winding to terminate the hunting movement and after a short delay period relay AR releases thereby opening the locking circuit to relay 2G, and at armature *ar5* releases relay CB so that the register controller thereupon commences to deliver the re-routing code as set up over the new position of the BC switch.

The operations which take place in respect of a party line call are substantially identical to those already described except that relay PL is operated in addition to relay CB, and at armatures *pl1* and *pl2* connects up the banks *6f* and *8f* of the sending switch SND, over which a different position is marked in the BC switch bank for the same routing digits dialled.

In case it should become necessary for the same party line re-routing and coin box re-routing to be delivered in respect of the dialling of two different codes, the tags in the translation field corresponding to wiper *6a* of both positions will be connected to the same marking contact in the sender switch bank *4f*, and consequently upon the release of the BC switch from either routing dialled the resetting position is the same in both cases.

For calls to the manual board subscribers are instructed to dial the digit 0 only, whereupon the wipers of the BC switch are raised to the 10th level from which relay MB, Fig. 8, is operated over the vertical wiper BCVW and at armatures *mb1*, *mb2* and *mb3* sets up the manual board code in the translating field, while armature *mb4* is wired to the cut-off terminal CO to effect the release of the register controller when the three manual board digits have been delivered. It will be noticed that although the units distributor switch moves to its second position only, a start circuit is completed to the sender switch by way of armature *mb5*, Fig. 7.

For special inquiry calls the subscribers are

instructed to dial the digits 90 in response to which the BC switch is set to a position from which relay MC, Fig. 9, is operated over wiper *1a* so that it locks over its upper winding to earth on the common holding conductor 41. Relay MC in operating at armature *mc2* provides for the first digit marking in the translating field, and at armature *mc3* prepares a circuit to the cut-off terminal CO which is effective after 5 counting digits have been delivered from the register controller.

The test clerk's telephone is accessible by the dialling of the digits 99 in response to which the BC switch wipers are set into a position from which relay TC is operated over wiper *1a* so that it locks via its upper winding to earth on the common holding conductor 41. Relay TC at armature *tc2* provides for the marking of the first digit in the translating field, and in addition to the remaining four digit markings made by way of the wipers *2a* to *5a* a further marking is made from armature *tc3*, Fig. 8, with the wipers of the control switch in their first numerical position. The cut-off terminal CO is connected up by way of armature *tc4* with the wipers of the control switch in their second numerical position. By this means as many as 6 translated digits are available for routing the call to the test clerk.

In case the presence of a fault renders the busying of the register controller desirable this may be effected by the operation of the busy key BK, which at springs *1bk*, Fig. 7, removes earth from the common holding conductor to release any apparatus which may be locked there-to, at springs *2bk*, Fig. 6, direct earth is connected to the test conductor 34 extending to the distributor switch thereby marking the circuit as busy, and at springs *3bk*, Fig. 7, the circuit is opened to the time pulse relay TP to prevent the continuous operation of the alarm.

If for any reason the BC switch fails to restore to its normal position upon the release of the register controller, earth by way of the resting springs of the busy key *1bk*, Fig. 7, is extended over armature *kb5* and off-normal springs *3N4* to the conductor 56 to set in operation a delayed alarm circuit which functions after the period for which it is set to provide an indication that a BC switch has failed to restore to its normal position.

I claim:

1. In a telephone system, calling lines of different types, means controlled by said lines for dialling a particular exchange code, register controllers responsive to the receipt of said exchange code for transmitting a series of routing digits, said routing digits transmitted by said register controllers being different in accordance with the type of line calling.

2. In a telephone system, calling lines, means controlled by said lines for dialling exchange codes, and means including register controllers operative in response to certain of said lines dialling an exchange code for transmitting a series of routing digits characteristic of the type of line calling independent of the exchange code dialled.

3. In a telephone system, a first and a second exchange designated by the same exchange code, a calling party, register controllers in said exchanges for transmitting a series of routing digits in response to the receipt of a particular dialled exchange code, and means for releasing or for further employing the register controllers in one

80

- of said exchanges to register and retransmit the remaining digits dialled by the calling party dependent upon the value of the first numerical digit transmitted thereto.
5. In a telephone system, a first and a second exchange designated by the same exchange code, a calling party in one of said exchanges, register controllers in said exchanges for transmitting a series of routing digits in response to the receipt 10 of a particular dialled exchange code, means for delaying the transmission of the routing digits from a register controller in the first of said exchanges until the first numerical digit has been stored on such register controller in response 15 to the calling party dialling said exchange code designating both exchanges, and discriminating means responsive to said first numerical digit for releasing said register controller in case such digit designates a local call or for further employing said register controller in setting up a connection in case such digit designates a call for the second exchange.
5. In a telephone system, calling lines, finders having bank contacts for terminating said lines, 20 a first numerical switch associated with each of said finders, register controllers, means responsive to a call by one of said lines for operating one of said finders to connect the calling line to the associated switch and for seizing one of said register controllers, the seized register controller responsive to the calling party on said line dialling digits for sending out routing digits corresponding thereto, incoming lines also terminating in the banks of said finders, means responsive to an 25 incoming call over one of said incoming lines for operating one of said finders to connect the incoming line to the associated switch, and means responsive to said last connection for transmitting a signal to prevent the seizure of a register controller and to alter the circuits of said switch from a selector having a directive and an automatic hunting movement to a connector switch having two directive movements.
6. In an automatic telephone system, party 30 lines wherein each subscriber is assigned a different directory number, each subscriber on a party line having a different ringing code, a final selector switch for completing connections to called subscribers' lines, a relay in said final selector switch, a circuit for operating said relay, means responsive to a subscriber on a party line initiating a connection to a subscriber on the same line by dialling the directory number of the called subscriber for completing said circuit to operate said relay, and 35 means responsive to the operation of said relay for applying the ringing code of the called subscriber to said line.
7. In a telephone system as claimed in claim 2 including a switch in each register controller, 40 means responsive to the exchange digits dialled by a calling subscriber for setting said switch in a corresponding position, means responsive to a particular type of line calling for transmitting a signal to the register controller taken into use, 45 means in said register controller responsive to the receipt of said signal for automatically releasing said switch from its set position and for automatically resetting said switch to a different position, and transmitting means in said register controller controlled by said switch in its different position for transmitting a different series of routing digits.
8. In a telephone system as claimed in claim 2 including a switch in each register controller, 50 means responsive to the exchange digits dialled by any calling subscriber for setting said switch in a corresponding position, means operative in case the calling subscriber's line is a pay station or a party line for transmitting a signal to the register controller taken into use, means responsive to the receipt of said signal for automatically releasing said switch from its set position and for automatically resetting said switch to a different position, and transmitting means controlled by the switch in its different position for transmitting a different series of routing digits.
9. In a telephone system as claimed in claim 3 including an exchange code switch and a first numerical storing switch in each register controller, means responsive to the calling party dialling the exchange code for setting said code switch corresponding thereto, means responsive to the calling party dialling the first numerical digit of the called number for operating said storing switch corresponding thereto, and means operative in case the stored first numerical digit designates a local call to the first exchange for delaying the transmission of the routing digits transmitted by the register controller and for releasing the register controller.
10. In a telephone system, as claimed in claim 4 including a first numerical storing switch for storing the first numerical digit dialled by the calling party, a selector switch in the first exchange, a relay in said selector switch, a circuit 105 for said relay including a wiper of the storing switch, means dependent upon the position said storing switch is operated to for completing said circuit to operate said relay, and means responsive to the operation of said relay for releasing 110 the register controller in use.
11. In a telephone system as claimed in claim 4 including a first numerical storing switch for storing the first numerical digit dialled by the calling party, a sender control switch in the 115 register controller for controlling the transmission delay, a start circuit including a wiper of said storing switch for said sender switch, and means for completing said start circuit to operate said sender switch in case the storing switch is operated to a position indicating a call to the second exchange.
12. In a telephone system, calling lines, register controllers for transmitting a series of routing digits characteristic of the type of line calling independent of the exchange code dialled by a calling subscriber, a finder switch operative responsive to a call by a party on any one of said lines for connecting the calling line to one of said register controllers, a code switch in said 130 register controller operated responsive to the exchange code digits dialled by the calling party to the exchange code position, a circuit including a vertical wiper of said finder, means responsive to a particular type of line calling for transmitting a signal comprising earth potential over said circuit to the register controller, means in said register controller responsive to the receipt of said signal for automatically releasing said switch and for automatically resetting said switch to a different position, and transmitting means in said register controller controlled by said switch in its different position for transmitting a different series of routing digits.
13. In a telephone system as claimed in claim 6 including a finder associated with said final selector switch, a wiper on said finder, a second relay in said selector switch operative to prepare a circuit for said first relay, and means for 150

transmitting a signal over said wiper to operate said second relay for preparing the operating circuit of said first relay.

14. In a telephone system as claimed in claim 6 including a finder associated with said final selector switch, a wiper on said finder, a second relay in said selector switch operative to prepare a circuit for said first relay, means for transmit-

ting a signal over said wiper to operate said second relay for preparing the operating circuit of said first relay, and means for completing said prepared circuit for said first relay in response to the calling party replacing his receiver at the 80 termination of the dialling operation.
